Primary Examiner — Sandra Snapp(74) *Attorney, Agent, or Firm* — Abbey A. Lopez**CLAIM**

The ornamental design for an air freshener device, as shown and described.

DESCRIPTION

FIG. 1 is an isometric view of an air freshener device, wherein the air freshener device is comprised of a front housing, a dome, and a rear housing;

FIG. 2 is a front view of the air freshener device;

FIG. 3 is a left view of the air freshener device;

FIG. 4 is a right view of the air freshener device;

FIG. 5 is a back view of the air freshener device;

FIG. 6 is a top view of the air freshener device; and,

FIG. 7 is a bottom view of the air freshener device.

The broken lines shown in the drawings illustrate portions of the air freshener device and form no part of the claimed design.
